UNITED STATES PATENT OFFICE.

EDWARD E. KLEINSCHMIDT, OF BROOKLYN, NEW YORK, ASSIGNEE TO KLEINSCHMIDT ELECTRIC COMPANY, INC., OF BROOKLYN, NEW YORK, A CORPORATION OF NEW YORK.

KEYBOARD TELEGRAPHIC TRANSMITTER.

1,317,506.

Specification of Letters Patent. Patented Sept. 30, 1919.

Application filed January 11, 1915. Serial No. 1,546.

To all whom it may concern:

Be it known that I, EDWARD E. KLEINSCHMIDT, a citizen of the United States, and a resident of the borough of Brooklyn, city 5 and State of New York, have invented certain new and useful Improvements in Keyboard Telegraphic Transmitters, of which the following is a specification.

The present invention relates to a keyboard transmitter adapted to store signals in advance of transmission and it is intended for use principally with printing telegraphs having a code of unit length.

The purpose of this invention is to provide a simple and efficient transmitter wherein the operation of the keyboard is independent of the transmission of the signals and to thereby render unnecessary extreme care on the part of the operator to prevent 20 striking keys too rapidly in succession. Also by storing signals in advance of their transmission, to permit a constant and regular transmission of signals at an even speed, and at the same time permitting the 25 operator to strike keys fast or slow, or to pause for changing or marking messages without affecting or stopping the transmission.

In carrying out this invention, I have provided a storage member which holds separated groups of pins adapted to be set in transmitting and non-transmitting positions by a keyboard selecting mechanism. Each separated group of pins in the storage member represents a character or symbol to be transmitted. After a group of pins is set up in the storage member, it is advanced a distance of one group by a solenoid magnet in circuit with a contact operated by the 40 keyboard. I prefer to separate the group of pins or circuit controllers so that the operator may easily read the characters he has set up in the storage member. This storage member is preferably in the form of a 45 wheel.

Mounted centrally with the storage wheel but separate therefrom is a transmitting head. In the transmitting head is mounted a set of circuit closers equal in number to 50 a group of pins. The circuit closers are pressed against successive groups of pins

and their open or closed position is effected by pins set in either transmitting or non-transmitting positions. Also mounted in the transmitting head is a magnet which 55 acts to withdraw the circuit closers from the pins while the transmitting head is rotated to engage the next group. Between the transmitting head and the storage wheel is an escapement mechanism which is operated by the magnet of the transmitting head 60 and allows the latter to turn relative to the storage wheel, one step or the distance of one group of pins each time the magnet of the transmitting head is energized. 65

To transmit signals from the transmitting head to the line and receiving apparatus, I provide a master transmitter. This device comprises a commutator having segments corresponding in number to the circuit closers of the transmitting head. Contacting with these is a brush carried by a shaft which is rotated at a constant speed. This brush is connected to the line and the segments are individually connected to the 75 circuit closers. An extra segment and brush is provided to control the circuit of the magnet mounted in the transmitting head.

In using my transmitter, the speed with which the brush of the master transmitter 80 revolves is set to approximately the speed at which the receiving apparatus will work most satisfactory. As the operator strikes the keys corresponding symbols are set up in the storage wheel and it is advanced 85 step by step by the solenoid magnet. The brushes of the master transmitter revolve at regular intervals and with each revolution the circuit of the magnet in the transmitting head is closed and the escapement between 90 the transmitting head and the storage wheel operated, thereby allowing the transmitting head to turn step by step in a direction opposite to that of the storage wheel. With each step of the transmitting head the circuit 95 closers mounted thereon are brought in contact with the raised pins of a group thereby closing contacts in circuit which circuits include segments in the commutator of the transmitter. The circuit closers of the 100 transmitting head are held in position against the raised pins during the entire time

that the line brush is traveling over the segments of the master transmitter and since the brush connects successively with the commutator segments, the characters set up in the storage wheel will be transmitted to the line and the receiving apparatus at a uniform speed by the master transmitter.

To enable the operator to reset a group of pins, or in other words erase a signal, I have provided a key in the keyboard which is connected to a lever carrying a plate large enough to depress an entire group of pins and to another lever which carries a feed pawl and acts to turn the storage wheel in a direction reverse from that which it is moved when it is advanced by the solenoid magnet.

In using my transmitter for sending code words, it is advisable that the setting up of the characters shall be at least ten letters ahead of the transmitting so that the operator may check up each word before it is transmitted. To prevent the transmitting from coming closer than a space of ten letters to the setting up mechanism, I provide a circuit breaker operated by the position of the transmitting head and included in the circuit of the escapement magnet, which acts to open the circuit of the latter when the transmitting head approaches to within ten characters of the setting up mechanism. A similar circuit breaker is included in the circuit of the storage wheel advancing solenoid and acts to open its circuit when the storage wheel is filled with untransmitted characters.

When operating my transmitter in connection with a page printing receiving apparatus, I provide a character counter to give indication to the operator of the exact position a letter will occupy in the line. This character counter comprises a ratchet carrying a pointer which moves over a graduated scale. Each step of the ratchet represents the space occupied by a letter in a line. The ratchet is advanced step by step by a feed pawl that is mechanically connected to the lever that advances the storage wheel. When the pointer shows that the number of characters are nearly sufficient to fill a line, a contact controlled by the ratchet is made and a warning lamp lighted. Operated by the carriage return key is a release mechanism for returning the ratchet and pointer to the zero position.

The invention will be understood by reference to the accompanying drawings in which—

Figure 1— is a side elevation of the complete machine, Fig. 2 is a sectional side elevation taken through the center of the machine; Fig. 3 is a rear elevation of the top part of the machine; Fig. 4 is a sectional plan view taken under the top plate of the machine; Fig. 5 is a detail plan view showing the storage wheel; Fig. 6 is a detail of

the escapement; Fig. 7 is a diagram showing the connections between the transmitting head and the segments of a commutator similar to that used in the Baudot system, also the connections to the circuit for the operating solenoid; Fig. 8 is a detail showing the method of operating the reverse feed lever from the keyboard; Fig. 9 is a plan view of the character counter; Fig. 10 a detail of the same and Fig. 11 is a detail of the depressing shoe.

Similar reference numerals indicate similar parts in several views.

Fig. 1— shows a keyboard selecting mechanism similar to that used in my keyboard tape perforator patented Feb. 3, 1914, #1,085,985. In the present machine I used precisely the same keyboard only that the number of T bars is less as there are but five units in the code for which this transmitter is designed. Since this keyboard is fully described and explained in the previous patent above referred to, I will describe only such parts as are necessary to make clear its connection with the present invention. The number 1 designates the keys which operate selecting bars 2. The selecting bars are notched to represent the various combinations comprising the code and operate T bars 3. The motion of the T bar is imparted to the link 4 by a connecting bar 5. The upper end of the connecting link 4 is connected to a lever 6. When a key bar is depressed a combination of T bars is also depressed and their motion imparted to the levers 6 which presses upward a similar combination of circuit controllers 7, Figs. 1, 2 and 5.

Operated by a separate T bar 8 is a bar similar to the bars 5, shown in Figs. 1 and 2, and carrying a contact 9 in circuit with the storage wheel advancing solenoid 10. When a key bar is depressed the contact 9 is closed and solenoid 10 energized. The plunger of solenoid 10 is connected to one end of a lever 11 as shown in Fig. 4. This lever turns about a fulcrum 12 and has connected to its opposite end a feed pawl 13, which engages the ratchet wheel 14, Figs. 2, 3 and 4. The ratchet wheel 14 is connected to a tubular shaft 15 which carries at its upper end the storage wheel 16. Also connected to the tubular shaft 15 is a ratchet wheel 17, the teeth of which are cut reverse to the ratchet 14. Engaging with the former is a feed pawl 18 and a stop pawl 19. A stop pawl 20 engages the ratchet 14. The feed pawl 18 is carried by a lever 21. The pawls 19 and 20 are pivoted on studs 22 and 23 mounted on the under side of base 24.

An interlocking member 25 is pivoted on a stud 26 mounted in the base 24 and engages with the projecting studs 13', 18', 19' and 20' of pawls 13, 18, 19 and 20. The normal position of the interlocking member 25 is the position shown in the draw-

ings. Attached to the lever 11 is a stud 11' which when the former is operated to withdraw the feed pawl 13 from position, engages the inclined surface 25' of the interlocking member 25, causing it to turn about its fulcrum 26 and lift from engagement with ratchet 17 the pawls 18 and 19, allowing the ratchet 17, tubular shaft 15 and storage wheel 16 to turn when fed forward 10 by the return motion of the feed pawl 13. A stud 21' is set in the lever 21 and acts on the inclined surface 25' to turn the interlocking member 25 in the opposite direction lifting pawls 13 and 20, when lever 21 is operated to turn the ratchet wheel 17. It will be seen from the description and drawings that this arrangement of interlocking member with the pawls and feed levers acts to definitely lock the turning movement of 15 20 the storage wheel at the end of every feeding impulse and permits the turning of the storage wheel in either direction.

The lever 11 is held in its retracted position by a spring 11' and acts to advance the storage wheel when the solenoid 10 is de-energized upon releasing of a key in the keyboard.

The lever 21 is operated by a back space or erasure bar 27 carrying at the opposite end a connecting link 28 which connects with a bell crank 29 pivoted in brackets 30 and imparting its motion to the lever 21 by a pin and socket connection 29', as shown in Fig. 8. When the erasure bar 27 is depressed the lever 21 is operated to draw the pawl 18 backward one tooth and when the bar 27 is released the spring 21' acts to return the lever 21 and erasure bar 27 to their normal position. Attached to the bell crank 40 29 is a lever 31 which connects with a depressing member 32 through the link 31'. When the erasure key 27 is depressed the depressing member 32 is brought down against a set of raised pins 7 restoring them 45 to their non-transmitting positions and when the erasure key 27 is released the storage wheel is turned back one step thus erasing a character.

The signals are transmitted from the pins 50 of the storage wheel by a transmitting head 33 carried by a tubular shaft 33', which has bearing in the tubular shaft 15. To the lower end of the tubular shaft 33' is fastened a gear 34 engaging with a gear segment 35 55 which is pivoted in the frame. To the segment 35 is connected a spring 35', the tension of which acts upon the former causing it to turn the transmitting head about its axis in a direction opposite to that of the storage wheel, when that is advanced by the lever 11.

Mounted on the transmitting heads are magnets 36 which when energized attract an armature 37 (see Fig. 2). The armature 65 37 is carried by a bracket 37' which is fas-

tened to a frame 38 mounted to slide in the transmitting head 33 and held in a retracted position by the spring 38'. To the under side of the frame 38 are fastened escapement dogs 39 which engage a ratchet 40 fastened 70 to the storage wheel 16 as shown in Fig. 6.

The number of teeth in the ratchet wheel 40 corresponds to the number of groups of pins in the storage wheel and each time the magnet 36 is energized and deenergized escapement dogs 39 acting upon the teeth of the ratchet 40 allow the transmitting head to turn a distance equal to one group of pins. Also mounted in the transmitting head is a group of circuit closers in the form of bell 80 cranks 41, each carrying on one arm a contact 41' which is held in open circuit position by a spring 42. The action of the spring 38' is to draw the frame 38 in a forward direction causing the lower arms of the bell 85 cranks 41 to engage with such pins of the storage wheel as have been set into transmitting position, and by turning the bell cranks close the corresponding contacts 41' with contact blocks 47.

Referring to Fig. 7, 43 represents a master transmitter or the distributor used in the Baudot system. The arm 44 carrying brushes 45 and 46 rotates at a uniform speed and in doing so the brushes contact with the 95 segments in the commutator rings. I have shown a set of these segments, A, B, C, D and E connected to the contact blocks 47 of the transmitting head. The connections between the contact blocks 47 and the segments of the commutator are through a pole 100 changer A¹, B¹, C¹, D¹, and E¹. The armatures of the pole changers are normally held against the contacts A², B², C², D² and E² by their springs, energizing all of the segments with current of similar polarities. The magnets A³, B³, C³, D³ and E³ of the pole changers are in circuit with corresponding contact bars 47 and when a given bell crank 41 is operated to close its contact 41', circuit is established through the contact bar 47 and the pole changer magnet which attracts its armature connecting the corresponding segment with current of opposite polarity.

A segment 48 is included in the circuit with the magnets 36 and is placed slightly in advance of the set of commutator segments that connect with the contact blocks 47. As the arm 44 revolves the brush 45 contacts 120 with the segment 48 and a circuit is closed to the ring 49, establishing a circuit through the wire connections 50, battery 51, circuit breakers 52 and magnets 36. The armature 37 will then be attracted and in carrying 125 with it the frame 38 will operate the escapement dogs 39, allowing the armature 37 to recede by action of the retracting spring 38' and causing the lower projections of the bell cranks 41 to contact with the raised pins 130

of the next group, thus closing corresponding circuits to the group of segments marked A, B, C, D and E, impulses from these segments will be transmitted to the line when 5 the brush 46 travels over them.

To prevent transmitting characters directly after they have been set up in the wheel so as to give the operator an opportunity to erase a character or even an entire 10 word, should he have made an error in striking the keys, I provide, referring to Fig. 4, a circuit breaker 52 included in the circuit 50. The circuit breaker 52 is actuated by a cam 53 attached to the segments 35. 15 Cam 53 engages the projection 52' of circuit breaker 52 to open it when the transmitting head comes to a position approximately within ten letters of the setting up mechanism, that is where the levers 6 act upon the pins 7. The position of cam 53 relative to segment 35 is adjustable, making it possible to set the device so that the transmitting will stop at any desired point or distance from the setting up mechanism. A circuit breaker 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 a depending rod 64 to the lever 11 so that when the lever is operated the feed pawl 62 will operate on the ratchet 59 to feed the same forward a distance of one tooth.

The travel of lever 61 is limited by stops 65 and 66 and to prevent the adjustment of these stops interfering with the travel of lever 11, I prefer to insert a spring 67 in the lever 61 which will take up any extra motion of the lever 11, spring 67 being sufficiently strong to operate the lever 61 to effectively feed the ratchet 59. Fastened to the ratchet 59 but insulated therefrom is a contact spring 68 which when contacting with the screw 68' closes the circuit of indicator lamp 69 through a battery 70. In practice this contact is adjusted so that the circuit will be closed when the pointer is within ten letter spaces of the end of the line.

When the pointer indicates that the line is filled, the operator depresses the carriage return key which sets up a signal in the storage wheel that will operate the carriage return mechanism of the printer. Operated by the carriage return key 71 is a bell crank 72 which acts on a release pawl 74. In disengaging from the ratchet segment the nose of the feed pawl 64 acts upon the feed pawl 62 to withdraw it from the ratchet 59 releasing the segment and allowing the pointer to resume the zero position. To prevent the feed pawls engaging the ratchet segment before the pointer is returned to the zero position, I provide a catch 75, which engages a projection of the feed pawl 74 when it is released from the ratchet holding it until a pin 76 fastened to the ratchet segment 59, strikes the catch 75 to release the feed pawl 74. I provide a spring 77 which acts on the segment 59 to return it and the pointer to the zero position when it is released. To cushion their return motion, I provide a dash pot and plunger 78.

The transmitter shown and described herein is designed for use with the Baudot system. In this system the alphabet is made up with five units which in my transmitter are represented by the groups of pins, circuit breakers and commutator segments. Although I have shown the present transmitter adapted to the Baudot system, its use is not limited to it but may be used as a transmitter for any printing telegraph system, it being necessary merely to change the code and for some systems the number of pins, circuit breakers and commutator segments in a group.

I have shown the circuit breakers 41 in a normally open position to suit the present construction. It is however evident that these may be also normally closed, or they may be constructed to both open and close. To make the change it is necessary only to fix the contacts either on the under side of

the upper arm of the bell crank, or if it is desired to both open and close contacts, to place contacts on both sides of the arm.

The words "circuit closers" mentioned in the claims are used as a convenience and describe the present construction. It is however, within the meaning of the phrase to use circuit breakers or contacts to both open and close.

10 What I claim and desire to secure by Letters Patent is:

1. In a telegraph transmitter, a storage member carrying groups of circuit controllers, means for setting up combinations of said groups of circuit controllers in transmitting and non-transmitting positions, a group of circuit closers, means to bring the circuit closers into engagement with groups of circuit controllers successively and a master transmitter to control the action of the circuit controllers upon the circuit closers.

2. In a telegraph transmitter, a movable carrier, circuit controllers carried thereby, a keyboard selecting mechanism to set the circuit controllers in transmitting position, a ratchet feed mechanism operated by an electromagnet to advance the movable carrier equal distances each time a key bar is operated, said ratchet feed mechanism comprising ratchets with reversed teeth, stop pawls engaging the said ratchets to hold same against moving in either direction, and means to disengage one of the stop pawls when the feed mechanism is operated.

3. In a telegraph transmitter, a movable carrier, circuit controllers carried thereby, a keyboard selecting mechanism to set the circuit controllers in transmitting position, feed mechanisms to advance or retract the movable carrier equal distances, comprising two ratchet wheels with opposite cut teeth, two feed levers respectively operating feed pawls, two stop pawls, said feed pawls and stop pawls engaging with the said ratchet wheels, and an interlocking member operated by the feed levers to disengage a feed pawl and stop pawl to permit turning the ratchet when the feed mechanism is operated.

4. In a telegraph transmitter, a movable carrier, circuit controllers carried thereby, a keyboard selecting mechanism to set the circuit controllers in transmitting position, a ratchet feed mechanism to advance or retract the movable carrier equal distances, feed pawls normally in engagement with the ratchets, an interlocking member and means to operate said interlocking member to disengage a feed pawl and stop pawl holding the said feed wheel against rotation in a given direction when the ratchet is to be turned by the feed mechanism in that direction.

5. In a telegraph transmitter, a movable carrier, circuit controllers carried thereby,

a keyboard selecting mechanism to set the circuit controllers in transmitting position, a fixed depressing shoe placed with relation to the movable carrier to restore the circuit controllers to non-transmitting position when the movable carrier is advanced, and a depressing shoe operated from the keyboard to restore the circuit controllers to non-transmitting position when the movable carrier is retracted.

6. In a telegraph transmitter, a movable carrier, circuit controllers carried thereby, a keyboard selecting mechanism to set the circuit controllers in transmitting position, means to advance the movable carrier equal distances, separate means to retract the movable carrier equal distances, an erasure bar, and a depressing shoe connected to said erasure bar to set a group of circuit controllers in non-transmitting position.

7. In a telegraph transmitter, a movable carrier, circuit controllers carried thereby, a keyboard selecting mechanism to set the circuit controllers in transmitting position, an erasure bar, a feed mechanism operated by the keyboard to advance the movable carrier equal distances, a separate feed mechanism to retract the movable carrier equal distances and operated by said erasure bar, and an interlocking member between the advancing feed mechanism and the retracting feed mechanism to disengage one when the other is operated.

8. In a telegraph transmitter, a movable carrier, circuit controllers carried thereby, a keyboard selecting mechanism to set the circuit controllers in transmitting position, a ratchet mounted on the movable carrier, a transmitting head, a slide mounted in the transmitting head, escapement dogs carried by said slide, an electromagnet mounted on the transmitting head coöperating with an armature mounted on the slide, and a spring to turn the transmitting head to engage the escapement dogs with the ratchet.

9. In a telegraph transmitter, a movable carrier, circuit controllers carried thereby, a keyboard selecting mechanism to set the circuit controllers in transmitting position, a transmitting head comprising a group of circuit closers and an electromagnet to bring said circuit closers into engagement with the circuit controllers, a master transmitter comprising contact devices, said contact devices connected individually to the circuit closers and a contact operated by the master transmitter to control the action of the magnet in the transmitting head.

10. In a telegraph transmitter, a movable carrier, adjustable circuit controllers carried thereby, a keyboard selecting mechanism to set the circuit controllers in transmitting position, means controlled by the keyboard to advance the movable carrier equal distances, a transmitting head carry-

ing a group of circuit closers to operate in conjunction with the circuit controllers, and means operated by the position of the transmitting head to control the advancing movement of the movable carrier.

11. In a telegraph transmitter, a movable carrier, circuit controllers carried thereby, a keyboard selecting mechanism to set the circuit controllers in transmitting position, a transmitting head carrying a group of circuit closers and a magnet to bring said circuit closers into engagement with successive groups of circuit controllers, a circuit breaker included in the circuit of said elec-
10 tromagnet, and means to control the open or closed position of said circuit breaker by the transmitting head.

12. In a telegraph transmitter, a character counter comprising a scale, a pointer operating in conjunction therewith, a ratchet to which said pointer is connected, a feed pawl coöperating with said ratchet and
20

means to operate said feed pawl to turn the ratchet each time a key bar is depressed, and a contact operated by the ratchet to ignite an indicator lamp.

25

13. In a telegraph transmitter, a character counter comprising a scale, a pointer operating in conjunction therewith, a ratchet to which said pointer is connected, a feed pawl coöperating with said ratchet and
30 means to operate said feed pawl to turn the ratchet each time a key bar is depressed, a retaining pawl coöperating with the ratchet and means to lift the retaining and feed pawls from engagement with the ratchet by
35 a key in the keyboard.

In testimony whereof I have hereunto signed my name in the presence of two subscribing witnesses.

EDWARD E. KLEINSCHMIDT.

Witnesses:

M. E. McNINCH,

CHARLES S. JONES.
